[57] CLAIM

The ornamental design for a blender cover, as shown and described.

DESCRIPTION

FIG. 1 is a perspective view of a blender cover, showing my new design, in position around a blender, shown in broken line for illustrative purposes only, and forming no part of the claimed design;

FIG. 2 is a front elevational view of the blender cover;

FIG. 3 is a rear elevational view of FIG. 2;

FIG. 4 is a top plan view of FIG. 2;

FIG. 5 is a bottom plan view of FIG. 2;

FIG. 6 is a right side elevational view of FIG. 2; and,

FIG. 7 is a left side elevational view of FIG. 2.
